UNITED STATES PATENT OFFICE.

PAUL H. WELCKER, OF ST. PAUL, MINNESOTA, ASSIGNOR TO BROWN & BIGELOW,
OF ST. PAUL, MINNESOTA, A CORPORATION OF MINNESOTA.

SYSTEM FILE.

Application filed September 17, 1920. Serial No. 410,848.

To all whom it may concern:

Be it known that I, PAUL H. WELCKER, a citizen of the United States, residing at St. Paul, in the county of Ramsey and State of Minnesota, have invented a new and useful Improvement in System Files, of which the following is a specification.

My invention relates to a system file, the primary object of which is to provide means for collectively holding correspondence consisting of letters and other papers in a collapsible file concealed in a neat and tidy manner so that instead of the office desk being mussed-up with papers they can be held together in an adjustable file under a particular index readily accessible when desired.

The invention consists of filing means which is collapsible into a flat thin state when empty, primarily designed to be used in connection with an office desk and having self-adjusting means to various thicknesses to accommodate letters and papers beneath separate sheets in a file which is adapted to hold the same collectively. This means of keeping correspondence papers upon which immediate action is desired affords a very desirable office utility and has a tendency to systematize the routine of work of the user.

A file of this nature is adapted to receive considerable use and a feature of the invention is in providing a very substantial manner in securing the dividing sheets to the main back of the file so that the strain either from pulling directly against the sheets or the wear of folding the sheets over on their hinged edge will not loosen the sheets from the back, which would very likely happen unless the sheets were attached in the peculiar manner in which I have illustrated in my invention.

It is essential to provide a substantial file, especially as a device of this kind will be used continually each day and it is preferred to have the outer portion and covering sheet thereof made of mission leather or other suitable strong material. The invention also includes suitable indexing means for each sheet of the file.

In the drawings forming a part of this specification:

Figure 1 is a perspective view of the sys-

tem file as it would appear in a collapsed state when little or no papers are contained therein.

55

Figure 2 is a perspective of the file in use illustrating it expanded, as it would adjust itself when papers are contained therein.

Figure 3 is a plan view of the file in open position.

60

Figure 4 is a perspective view of the portion of one of the dividing sheets illustrating the engaging tongues.

Figure 5 is a similar view to Figure 4.

Figure 6 is a plan view of one corner of the dividing sheets illustrating the label attaching means for receiving the index for the sheets.

Figure 7 is an edge view of the portion illustrated in Figure 6.

70

The drawings illustrate the system file A made up of a series of separating sheets 10 which are associated with a preferably stiff back 11. An adjustable portion 12 formed of stiff material similar to the back 11 is hinged at 13 to the back and carries the cover 14 hinged along the edge 15 thereto. The cover 14 is preferably of mission leather or other suitable material and may be provided with a paper, leather or other suitable lining, being positioned in relation to the sheets 10 so as to practically conceal the same and act as a cover for the file.

75

When the file A is empty it falls into a collapsed state of itself as illustrated in Figure 1. In use of the file A papers consisting of correspondence, letters, or other material are filed beneath the cover and between the sheets 10 and as the contents of the file increases it will automatically adjust itself, raising the portion 12 into the slanting position illustrated in Figure 2 to form a neat compact file with the cover 14 lying comparatively parallel with the base or back 11. The self-adjusting of the file is an important feature as it always gives a tidy appearing means for holding desk papers and correspondence.

85

Attached to one corner of each of the sheets 10 and the cover 14 is a label holder 16 which is adapted to receive a card 17 on which can be written or printed suitable indexing or reference data after which the card is covered by a transparent

90

95

100

portion 18 made of celluloid or other suitable material. The label holder 16 is attached in a suitable manner to the corners of each sheet and to the cover of the system 5 file A.

The sheets 10 have their free ends covered with a piece of leather 19 or other suitable well wearing material to protect these ends which receive a good deal of wear by handling and when the file is in use the free ends of the sheets project one below the other in consecutive order so that the ends of each sheet is exposed from beneath the end of the cover 14. This is true of the 10 sheet even when the file is in use with papers between the same, as the portion 12 tends to extend on a slant and thus expose the free ends of the sheets.

Each of the sheets 10 are formed with a 20 series of oppositely projecting tongues 20 and 21 respectively, which are glued or otherwise attached to the inner surface of the portion 12 to securely attach the sheets in the file. By this peculiar construction any 25 direct pull on the sheets 10 is transmitted to either side of the hinged edge 22 of each of the sheets, thus evenly distributing the strain on either side of the sheet and tending to form a strong attaching means for the 30 sheets. The tongues 20 and 21 mesh with each other as illustrated in Figure 3 so as to give a flat engaging attaching means at the hinge of each sheet and prevent bulging of the sheets at the hinging point when the file 35 is folded or collapsed.

When the system file A is in use it simulates a parallelepiped in shape as is illustrated in Figure 2. The file at all times adjusts itself in accordance with the thickness 40 of the material inserted between the leaves of the same. It never tends to bulge at the top where the leaves are hinged and secured together. The member 12 adjusts the position of the separating leaves 10 due to the 45 hinging of the same along the edge 13 of the back 11.

The separating sheets 10 are equally spaced apart and attached to the head portion 12 of the file A. This construction permits them to be self, or automatically adjustable when material is inserted between them up to the maximum space of separation between the points of their attachment, thus papers can be inserted in the file A 50 without bulging the sheets at the hinging point up to the thickness of the space separating the sheets from the back and adjustable head portion 12.

In accordance with the patent statutes I 60 have described the principles of operation of my invention together with the construction, which I believe to be the best embodiment thereof, but I desire to have it understood that the invention may be applied to other

uses within the scope of the following 65 claims:

I claim:

1. The combination of a back member, a cover member, a member interposed between said back and cover, means for hingedly securing said members together in a manner to cause said back and interposed member to lie in the same plane when said members are folded together, a series of separating sheets, and means extending from either side 70 of said sheets along one edge thereof adapted to hingedly attach said sheets to said interposed member in a manner to secure said sheets on either side of the line of hinging thereof to securely hold them to said back. 75

2. A self-adjusting file including a front and back portion, a member hinged to and interposed between said front and back portion, a series of separating sheets, attaching tongues formed integral with and extending 80 from either side along one edge of said sheets adapted to attach said sheets to said interposed member with said tongues extending in the same plane.

3. A self-adjusting file comprising, a 90 front member, a back member, an adjusting member interposed between said front and back member and hingedly secured thereto, a series of separating sheets and a series of attaching tongues projecting from said 95 sheets, adapted to hingedly attach said sheets to said adjusting member, said attaching tongues being adapted to intermesh to form a comparatively flat attachment with 100 said adjusting member.

4. A self-adjusting file comprising a back, a cover hingedly secured to said back on one edge and a cover hingedly secured to the other edge of said member, a series of separating sheets positioned between said cover 105 and back and intermeshing edge tongues formed on said sheets adapted to be attached in a single plane to said back.

5. A combination of a back, a cover, a member interposed between said back and 110 cover and hingedly secured thereto, a series of separating sheets and means projecting from said sheets adapted to intermesh with the means projecting from the adjacent sheets, whereby said sheets are attached to 115 said interposed member with the attaching means extending in a single plane.

6. A self-adjusting file comprising a back, a cover member, a head member interposed and hingedly secured to said back and cover, 120 a series of separating sheets and attaching tongues projecting from said separating sheets adapted to intermesh with the tongues of the adjacent sheets, all of said tongues being secured to said head member in substantially the same plane.

PAUL H. WELCKER.
